US0D1108285S

(12) **United States Design Patent** (10) **Patent No.:** **US D1,108,285 S**
(45) **Date of Patent:** **** Jan. 6, 2026**

(54) **PASSIVE SAMPLER FOR ENVIRONMENTAL
WATER MONITORING**

(71) Applicant: **Battelle Memorial Institute**,
Columbus, OH (US)

(72) Inventor: **Eliza M. Kaltenberg**, Quincy, MA
(US)

(73) Assignee: **Battelle Memorial Institute**,
Columbus, OH (US)

(**) Term: **15 Years**

(21) Appl. No.: **29/768,224**

(22) Filed: **Jan. 28, 2021**

CLAIM

The ornamental design for a passive sampler for environmental water monitoring as shown and described.

DESCRIPTION

FIG. 1 is an enlarged front, left, top perspective view of the claimed design;

FIG. 2 is a front view of the claimed design of FIG. 1;

FIG. 3 is a top view of the claimed design of FIG. 1;

FIG. 4 is a bottom view of the claimed design of FIG. 1;

FIG. 5 is a left side view of the claimed design of FIG. 1;

FIG. 6 is a right side view of the claimed design of FIG. 1;

and,

FIG. 7 is a rear view of the claimed design of FIG. 1.

The broken lines shown in the drawings are included for the purpose of illustrating portions of the passive sampler for environmental water monitoring and form no part of the claimed design.

1 Claim, 2 Drawing Sheets
